UNITED STATES PATENT OFFICE.

ROLLIN C. LEWIS, OF STAMFORD, CONNECTICUT, ASSIGNOR TO THE YALE & TOWNE MANUFACTURING COMPANY, OF STAMFORD, CONNECTICUT.

DIAL-LOCK.

1,395,845.

Specification of Letters Patent.

Patented Nov. 1, 1921.

Application filed April 5, 1921. Serial No. 458,690.

To all whom it may concern:

Be it known that I, ROLLIN C. LEWIS, a citizen of the United States, and a resident of Stamford, in the county of Fairfield and 5 State of Connecticut, have invented certain new and useful Improvements in Dial-Locks and I do hereby declare the following to be a full, clear, and exact description of the invention, such as will enable others 10 skilled in the art to which it appertains to make and use the same.

This invention relates to an improvement in dial locks.

Locks of this type are sometimes attacked 15 by first removing the dial and driving the spindle back into the lock case. The inner end of the spindle contacting with the curb, or the driving cam on the spindle contacting with the first tumbler of the series, 20 which tumblers are carried by the curb, dislodges the curb and its associated tumblers and also the driving cam on the spindle thus removing the bolt locking means and 25 permitting the bolt to be retracted from the outside.

The object of this invention is to provide means for normally deadlocking the bolt, and a safety device which moves into position upon the displacement of the driving 30 cam, for holding the deadlocking means in its deadlocking position and thus prevent the retraction of the bolt.

With this object in view my invention consists in the parts and combination of parts 35 as will be more fully explained and pointed out in the claims.

In the accompanying drawings, Figure 1 is a view in perspective of the dial, lock case, spindle, driving cam on the spindle 40 and the combined fence and deadlocking lever; Fig. 2 is a view of the curb and the disk tumblers carried thereby; Fig. 3 is a view in section of Fig. 4 and Fig. 4 is an end view of the lock case, the curb, tumblers, 45 driving cam and spindle being removed.

10 represents the dial and 11 the spindle which connects the dial with the driving cam 12 which as shown in Fig. 1 is keyed to the spindle 11 and turns therewith. This 50 driving cam 12 is located within the lock case 13, and actuates the tumblers 14 in the well known manner. These tumblers are assembled and secured on a sleeve 15 integral with the curb 16, and the latter is secured to the open end of the lock case with

the first tumbler thereon in position to be engaged and actuated by the driving cam.

As the lock case 13 is secured to the inner face of the door, and the tumblers assembled on and secured to the curb which is secured to the lock case, it follows that if the curb be forcibly detached from the lock case, by driving the spindle inwardly, the tumblers will also be dislodged and fall out with the curb.

The tumblers and driving cam are each provided with a slot or gating 19, and the fence 17 which is integral with the dog or dead locking lever 18 normally rests against the peripheries of the tumblers and driving cam and holds the free end of the dog 18 up and in position to dog or deadlock the bolt. When the tumblers are turned by the dial spindle and driving cam to bring the gatings into alinement, the fence enters the 75 latter thus permitting the free end of the dog which is pivoted to the lock case at 20, to drop away from the bolt and permit the latter to be retracted.

My invention as previously stated, consists in applying to a lock of the type above described, a safety device that will come into action in the event the tumblers and driving cam are displaced, and prevent the dog or dead locking lever 18 from dropping and thus releasing the bolt and it consists of a plate 21 of a size and shape to fit within the lock case in front of the driving cam, and adapted to be forced out by a spring 22 and obstruct the movement of the fence 17 90 in the event of the displacement of the driving cam.

This plate is provided at its upper end with a projection 23 which rests in a slot in the lock case and prevents displacement of the plate, and is also provided centrally with an opening 24 for the passage of the spindle 11. The spring 22 rests between the front face of the lock case and the plate 21 and tends to force the lower end of latter 100 outwardly as shown in Fig. 3, but is normally held in the position shown in dotted lines by the driving cam 12 which when in normal position holds the plate against the front face of the lock case. If however the 105 driving cam be forced rearwardly or inwardly by force applied to the spindle, the plate 21 will be forced inwardly by its spring 22 as the cam 12 is moved rearwardly, and engages the fence and prevents the lat- 110

ter from rising as it would do if unobstructed.

It will therefore be seen that if the driving cam be displaced in efforts to release the lock, the safety plate 21 will move to a position over the fence and absolutely prevent the latter from rising as it must do to release the bolt.

In the ordinary operation of the lock, the 10 plate 21 is held out of the path of the fence and it is only when the driving cam has been displaced that this plate moves to a position to engage and obstruct the movement of the fence and consequently the 15 dogging lever 18 integral with the fence.

It is evident that numerous changes in the details of construction may be resorted to without departing from the spirit of my invention hence I would have it understood 20 that I do not confine myself to details except such as may be referred to in the claims.

Having fully described my invention what I claim as new and desire to secure by Letters-Patent, is:

25 1. In a lock, the combination of a spindle, a tumbler actuated by the same, a fence co-operating with the tumbler to dog and to release the bolt and means normally held out of the path of movement of the fence, but adapted to be positively moved into position to obstruct the unlocking movement of the fence if the tumbler be moved from its normal position with relation to the fence.

2. In a lock, the combination of a spindle, 35 a driving cam thereon, a tumbler actuated by the driving cam, a fence co-operating with the tumbler to dog and to release the bolt, and means normally held out of the path of movement of the fence by the driving cam 40 and adapted to move rearwardly or inwardly to a position over the fence in the event the driving cam be forced rearwardly.

3. In a lock, the combination of a spindle, a driving cam thereon, a tumbler actuated 45 by the driving cam, a fence co-operating with the tumbler to dog and release the bolt, a

safety device normally held out of the path of movement of the fence by the cam and a spring for moving the safety device into the path of movement of the fence in the event 50 of the displacement of the cam.

4. In a lock, the combination of a fence for dogging the bolt, means co-operating with the fence to permit the latter to move to release the bolt, and a safety device normally held in inoperative position by said co-operating means, but adapted, in the event of the displacement of the latter, to move into the path of movement of the fence and hold the same in its locking position. 55

5. In a lock, the combination of a lock case, a spindle, a dial and driving cam on the spindle, the driving cam being located within the lock case, tumblers actuated by the cam, a fence and a spring pressed safety 65 plate located in front of the cam and normally held in inoperative position by the latter but adapted to be moved into the path of movement of the fence in the event the cam be displaced rearwardly or inwardly. 60

6. In a lock, the combination of a lock case, a spindle, a dial and driving cam on the spindle, the driving cam being located within the lock case, tumblers also located within the lock case and actuated by the driving 75 cam, a fence co-operating with the tumblers, and a spring pressed safety plate located in front of the cam and provided with a projection resting within a slot in the case, the said plate being normally held in inoperative 80 position by the cam but adapted to be moved by its spring into the path of movement of the fence in the event the cam be displaced inwardly.

In testimony whereof, I have signed this 85 specification in the presence of two subscribing witnesses.

ROLLIN C. LEWIS.
